UNITED STATES PATENT OFFICE.

RICHARD MOORE, OF OSSINING, NEW YORK.

PEN-CLIP.

1,333,765.

Specification of Letters Patent. Patented Mar. 16, 1920.

Application filed August 15, 1918. Serial No. 250,054.

To all whom it may concern:

Be it known that I, RICHARD MOORE, a citizen of the United States, residing at Ossining, in the county of Westchester, State of New York, have invented certain new and useful Improvements in Pen-Clips; and I do hereby declare the following to be a full, clear, and exact description of the invention, such as will enable others skilled in the art to which it appertains to make and use the same.

The invention relates to a clip and more particularly to the class of pen or pencil clips.

The primary object of the invention is, the provision of a clip of this character, wherein a pen or pencil can be mounted therein for the safe carriage thereof in a pocket to avoid accidental loss of the same, the clip being of novel form to assure the holding and convenient removal of the pen or pencil from the pocket when desired.

Another object of the invention is, the provision of a clip of this character, which is extremely simple in construction, capable of engaging pens or pencils of different cross sectional diameters and will positively hold the same in the pocket of the user, and also one which is inexpensive to manufacture.

With these and other objects in view, the invention consists in the features of construction, combination and arrangement of parts as will be hereinafter fully described, illustrated in the accompanying drawing and pointed out in the claims hereunto appended.

In the accompanying drawing:

Figure 1, is a fragmentary elevation of a fountain pen showing the clip constructed in accordance with the invention, applied.

Fig. 2, is a perspective view of the clip removed from the pen.

Fig. 3, is a vertical sectional view through the clip.

Fig. 4, is a plan view of the blank from which the clip is made.

Similar reference characters indicate corresponding parts throughout the several views in the drawing.

Referring to the drawing in detail, A, designates generally a portion of a fountain

pen, the same being illustrated merely to show the application and the manner of use of the clip, as the same can be mounted upon a pencil, or the like, the clip being hereinafter fully described.

The clip comprises a split resilient sleeve or collar 5, preferably made from cold rolled machine steel, or, of any other suitable material and is formed from a substantially T-shaped blank B, shown in Fig. 4, of the drawing, the shank or stem of the T-shaped blank being folded or bent back on itself at the upper edge of the sleeve or collar 5 to provide a hook 6 outside of the sleeve or collar diametrically opposite the slit or split portion thereof, and this hook 6 is adapted to engage the facing portion of the pocket in a garment when it is desired to hold the pen, pencil or the like carried by the clip therein.

Threaded transversely through the hook 6 at some distance from its free end is a screw 7 having a knurled head 8, the inner end of the screw 7 being upset or spread at 9 to prevent the removal of the screw 7 from the hook, which screw is adapted to positively fasten the clip engaged with the pocket when supporting a pen or pencil.

In the path of movement of the screw 7 and formed in the sleeve itself, is an aperture 10, so that said screw can be worked inwardly in the hook 6 to bind the cloth of the pocket against the pen or pencil within the sleeve or collar 5, for the positive fastening of the clip and the pencil to the pocket.

The clip in its particular construction can be applied to wearing apparel, such as a shirt, to be used as a necktie clasp.

The resiliency of the sleeve or collar 5 permits the firm gripping of a pen or pencil, respectively, of any variance in the cross sectional diameter thereof.

From the foregoing it is thought, that the construction and manner of use of the clip will be clearly understood and therefore a more extended explanation has been omitted.

What is claimed is:

1. A pen or pencil clip comprising a single blank bent to form a split resilient sleeve and a hook opposite the split thereof, and a screw threaded through the hook to

work toward and away from the sleeve and having an upset inner end to prevent the removal of the screw from the hook.

2. A pen or pencil clip comprising an up-
5 right sleeve having a hole in one side, a hook bent from the upper end of the sleeve outward and its bill leading downward past said hole, and a set screw threaded through

the bill and alined with said hole, for the purpose set forth.

In testimony whereof, I affix my signature, in the presence of two witnesses.

RICHARD MOORE.
